UNITED STATES PATENT OFFICE.

DAVID W. BUCK, OF RHODES, IOWA.

BARREL-SLING.

1,145,292.

Specification of Letters Patent.

Patented July 6, 1915.

Application filed October 9, 1914. Serial No. 865,909.

To all whom it may concern:

Be it known that I, DAVID W. BUCK, a citizen of the United States, residing at Rhodes, in the county of Marshall and State 5 of Iowa, have invented new and useful Improvements in Barrel-Slings, of which the following is a specification.

The general object of this invention is to permit receptacles of the bilge type, those 10 having a uniform diameter throughout their length, or those having an increasing diameter from one end to the other, to be positively held in a suspended position to more easily effect the tilting thereof. And 15 to this end the invention consists of a frame having a companion pair of yoke members pivotally arranged therein, and adapted to embrace around the circumference of the receptacle, one of the yoke members includ- 20 ing a pair of flexible elements arranged in spaced relation and capable of independent adjustment of each other.

With these and other objects in view, the invention consists of certain novel features 25 of construction, combination and arrangement of parts, as will be hereinafter described and claimed.

In the accompanying drawings: Figure 1 is a perspective view of the barrel rack 30 complete. Fig. 2 is a front elevation thereof. Fig. 3 is a view of one of the companion members removed from the frame. Fig. 4 is a similar view of the companion member showing the same detached from the mem- 35 ber shown in Fig. 3. Fig. 5 is a perspective view of a cleat employed for holding the companion yoke members shown in Figs. 3 and 4 in operative position.

Referring to the drawings, numeral 1 des- 40 ignates a frame which is composed of a base 2, and vertical standards 3 which have their lower ends secured to the base and suitably braced as at 4, so as to provide a more rigid structure, the inner faces of the standards 45 being provided at their upper ends with opposed vertical grooves terminating at their lower ends in enlarged mouths 5.

Positioned within the standards 3 is a yoke member 7, which is formed of a strip 50 of metal and has its opposite ends terminating in trunnions 8 and 9 adapted to be received and journaled in the enlarged mouths 5 in the standards 3. Associated with the yoke 7 is a companion yoke mem- 55 ber 10 formed of a rod of flexible metal bent upon itself as at 11 and looped around

the trunnion 8 of the yoke member 7, and providing a pair of gripping members 12 and 13 which, as shown, are curved in a reverse direction to the curvature of the yoke member 7 and completes therewith a circular band adapted to embrace around a cylindrical receptacle as shown in Figs. 1 and 2 so as to hold the receptacle in suspended position and permit the same to be 60 tilted on the trunnion 8 when it is desired to empty the contents of the receptacle. The free ends of the members 12 and 13 are threaded as shown at 14 and 15, and when the companion yoke members are associated, 65 the said free ends of the members 12 and 13 are adapted to straddle the upper and lower surface of the adjacent trunnion 9 of the yoke member 7 and to be loosely received by openings 16 and 17 in a cleat member 18 70 and to be held therein by means of wing nuts 19 and 20 which are adapted to be adjusted against the sides of the cleat, the said cleat 18 being adapted to engage against the adjacent trunnion 9 of the yoke mem- 75 ber 7 and to retain the members 11 and 12 in semi-circular formation.

By virtue of the flexibility of the members 11 and 12 and the manner of securing their free ends to the adjacent trunnion 9, 80 it will be seen that each member may receive adjustment independently of the other, thereby permitting the members to be adjusted to the same degree to accommodate a receptacle of a uniform diameter 85 throughout its length or to be adjusted to different degrees to accommodate receptacles having a tapering body. In either case, it will be seen that the outer surface of the receptacle will be gripped at spaced 90 points and positively held from slipping. 95

What I claim as new is:

1. In a barrel rack, a supporting frame, a yoke pivotally mounted in the said frame, and embracing the barrel through a part of 100 its circumference, and relatively flexible elements arranged in spaced relation and supported on the yoke and embracing the barrel through the remaining part of its circumference as and for the purpose specified. 105

2. In a barrel rack, a supporting frame, a yoke pivotally mounted in the said frame, and embracing the barrel through a part of 110 its circumference, and relatively flexible elements arranged in spaced relation and supported on the yoke, and embracing the barrel through the remaining part of its cir-

cumference, and means for holding the said elements against relative lateral movement when in operative position.

3. In a barrel rack, a supporting frame, a yoke pivotally mounted in the said frame, and embracing the barrel through part of its circumference, and relatively flexible elements arranged in spaced relation and supported on the yoke and embracing the barrel through the remaining part of its circumference, and adjustable independently of each other as and for the purpose specified.

4. In a barrel rack, a supporting frame, a

yoke pivotally mounted in said frame and embracing the barrel through part of its circumference and relatively adjustable flexible elements arranged in spaced relation and supported on the yoke and embracing the barrel through the remaining part of its circumference, and means for adjusting the said elements.

In testimony whereof I affix my signature in presence of two witnesses.

DAVID W. BUCK.

Witnesses:
